HOOK

Charles B. Patton, 1507 Kingsley, Dallas, Tex. 75216

Filed Apr. 2, 1965, Ser. No. 84,586

Term of patent 3½ years

(Cl. D41—1)

FIG. 1 is a front elevational view of a hook showing my new design, the thickness being uniform throughout.

FIG. 2 is a similar view on a reduced scale, the broken lines being for illustrative purposes only.

I claim:

The ornamental design for a hook, as shown and described.
